UNITED STATES PATENT OFFICE.

WALTER I. TUTTLE, OF PROVIDENCE, RHODE ISLAND, ASSIGNOR TO FRANK MOSSBERG COMPANY, OF ATTLEBORO, MASSACHUSETTS, A CORPORATION OF RHODE ISLAND.

RATCHET WRENCH.

1,426,127.

Specification of Letters Patent. Patented Aug. 15, 1922.

Application filed April 23, 1920. Serial No. 375,935.

To all whom it may concern:

Be it known that I, WALTER I. TUTTLE, of Providence, in the county of Providence, State of Rhode Island, a citizen of the 5 United States, have invented an Improvement in Ratchet Wrenches, of which the following is a specification.

This invention relates to ratchet wrenches and the like. One of the objects thereof is 10 to provide a construction for devices of the above nature characterized by simplicity and practicability in a marked degree. Another object is to provide a device of the above nature of highly efficient action and 15 strong and durable in construction. Other objects will be in part obvious and in part pointed out hereinafter.

The invention accordingly consists in the features of construction, combinations of 20 elements and arrangement of parts which will be exemplified in the structure herein-after described and the scope of the application of which will be indicated in the following claims.

25 In the accompanying drawings in which is shown one of various possible embodiments of this invention,

Figure 1 is a plan, certain parts being removed and broken away in order to show 30 the construction more clearly;

Figure 2 is a sectional view along the line 2—2 of Figure 1; and

Figure 3 is a sectional view along the line 3—3 of Figure 1.

35 Similar reference characters refer to similar parts throughout the several views of the drawings.

Referring now to the drawings in detail, there is shown a wrench handle 10 having 40 cast integral therewith a head portion 11. This head portion is of a general annular form except where it merges into the handle 10, and is provided with an inwardly directed flange 12 the edge portion of which is 45 circular to serve as a bearing.

The thickness of the head portion 11 is reduced with respect to that of the handle 10 at the shoulder 13 against which abuts a cover member 14 held in place as by the 50 rivets 15. This cover member is provided with a circular opening 16 adapted to serve

as a bearing and is substantially equal to the bearing formed in the flange 12.

Mounted within the head is a ratchet 17 provided with outwardly directed shoulders 55 18 respectively fitted in the above bearings of the flange 12 and opening 16. The teeth of the ratchet proper are so formed as to clear the inner wall of the head as at 19 and thus permit free rotation of the ratchet 60 within the head. It may here be noted that the term "ratchet" is herein used in a broad sense to denote, unless otherwise modified, any toothed member, the teeth of which are adapted to co-act with a dog or pawl. 65

Centrally formed in the ratchet 17 is an opening 20 of non-circular configuration in order to fit over a nut, the latter term being broadly used to denote any part with which the wrench may co-act for the purpose of 70 turning the same. A ball 21 is preferably mounted in the walls of the opening 20 and outwardly spring-pressed in the well known way in order to adapt it to exert frictional pressure on the nut and prevent the latter 75 from dropping out of the wrench in use.

Formed in the head 11 and preferably extending through an integral offset 22 in the handle 10 is a recess 23 preferably of circular conformation as indicated in Figure 3 80 of the drawings.

Secured in this wrench is a slidable dog or pawl 24 having a circular portion formed in its lower end into which fits a coiled spring 25. This spring normally urges the pawl 85 in a direction toward the ratchet 17 and the pawl is preferably so mounted as to be directed substantially toward the center of the ratchet. The active end of the pawl at 26 is so shaped as to form an edge 27 between the flattened surfaces 28 and 29. This end portion of the pawl is flattened as at 27^a to be engaged by the cover 14 which thus holds the pawl from rotating and yet permits the use of round stock for the latter 95 which is of relatively low cost.

In the action of the device if the wrench be swung in the direction indicated by the arrow in Figure 1 of the drawings, the inclination of the surface 28 on the pawl fitting 100 the adjacent teeth of the ratchet, is such that the component of the force directed axi-

ally of the recess 23 will overcome the friction of the parts and the force of the spring 25, and cause the pawl to recede bodily into the recess and permit the teeth of the ratchet 5 to snap past the same.

The surface 29 of the pawl, however, together with the surface of the ratchet teeth against which it abuts, are so formed that upon the head being swung in a direction 10 opposite to that indicated by the arrow, the pawl will lock itself in position. In other words, this surface is so abrupt that the friction of the parts will jam the pawl into position and prevent the relatively small 15 component of force extending longitudinally of the recess, from causing the pawl to recede.

Thus assuming that the opening 20 is fitted over a nut which it is desired to turn, 20 if the head be swung in the direction indicated by the arrow, the nut with the ratchet will be unaffected as the dog snaps over the several ratchet teeth. On the other hand, if the wrench be swung in the opposite direction, the pawl will jam or lock itself in position and rotate the ratchet and the nut fitted 25 therein.

It will thus be seen that there is provided a device in which the several objects of this 30 invention are achieved and that although the parts are few in number and of extreme simplicity, nevertheless their action is thoroughly effective and dependable.

As various possible embodiments might be 35 made of the above invention and as various changes might be made in the embodiment above set forth, it is to be understood that all matter herein set forth or shown in the accompanying drawings is to be interpreted 40 as illustrative and not in a limiting sense.

I claim as my invention:—

1. In construction for ratchet wrenches and the like, in combination, means comprising a ratchet adapted to engage and turn a 45 nut, a mounting for said ratchet through which said ratchet is turned and provided with a substantially round recess directed toward said ratchet, a round pawl fitting said recess, and a spring within said recess 50 urging said pawl toward said ratchet to lock said ratchet against relative turning in one direction, said pawl being provided at its engaging end with a pair of flattened surfaces angularly disposed with respect one to another and adapted to fit between the teeth 55 of said ratchet and with a flattened lateral bearing portion adapted to hold said pawl against rotation in its recess.

2. In construction for ratchet wrenches 60 and the like, in combination, a pair of members one of which is adapted to engage and turn a nut, and through the other of which turning force is applied to the first member, a ratchet formed on one of said members 65 and a cylindrical recess flattened at one end

formed in the other member, a round pawl mounted to slide in said recess and provided with a flattened lateral bearing portion adapted to hold said pawl against rotation in the recess therefor, and a spring urging 70 said pawl toward said ratchet, said pawl being adapted to co-act with said ratchet and in one direction of relative rotation to permit said ratchet to slip past by bodily recession within said recess, and in the other 75 direction of rotated force to lock said first members one to another.

3. In construction for ratchet wrenches and the like, in combination, a ratchet provided with an opening to fit over and turn 80 a nut, a member having a portion adapted to mount said ratchet and permit the same to rotate therein and a portion serving as a handle through which said ratchet is turned, said last member having a cylindrical recess 85 formed therein extending toward said ratchet and inclined outwardly into a projection on said handle, a pawl movable endwise to a limited extent within said recess to lock said ratchet, and a spring within said 90 recess urging said pawl toward said ratchet.

4. In construction for ratchet wrenches and the like, in combination, a ratchet provided with an opening adapted to fit over and turn a nut and with a pair of circular 95 shoulders respectively formed on its sides, a mounting for said ratchet having a handle portion, a portion enclosing the ratchet and consisting of a flange forming a portion for one of said shoulders, and a cover part secured to said mounting by screws to embrace and form a bearing for the other shoulder of said ratchet and hold said ratchet against sidewise movement, and a round pawl 100 slidably fitted within a cylindrical recess in 105 said projection on said handle and shaped to co-act with the teeth of said ratchet and permit relative turning in one direction and lock the parts against relative turning in opposite direction, said pawl being provided with 110 a flattened lateral bearing portion adapted to cooperate with a corresponding bearing portion in said cylindrical recess to prevent the rotation of said pawl in said recess.

5. In construction for ratchet wrenches 115 and the like, in combination, a ratchet provided with an opening adapted to fit over and turn a nut and with a pair of circular shoulders respectively formed on its sides, a mounting for said ratchet having a handle portion, a portion enclosing the ratchet and an integral flange forming a portion for one of said shoulders, a cover part secured to said mounting to embrace and form a bearing for the other shoulder of said ratchet 120 and hold said ratchet against sidewise movement, a pawl provided with a cylindrical pocket in one end thereof and slidably fitted within a recess in said mounting and shaped to co-act with the teeth of said ratchet and 130

permit relative turning in one direction and lock the parts against relative turning in the opposite direction, and a coiled spring within said recess and entering said pocket 5 tending to force said pawl out of said recess into engagement with said ratchet, said pawl being provided with a flattened lateral bearing portion adapted to cooperate with a cor- responding bearing portion in said cylindrical recess to prevent the rotation of said pawl in said cylindrical recess.

In testimony whereof I have signed my name to this specification this 12th day of April, 1920.

WALTER I. TUTTLE.
